UNITED STATES PATENT OFFICE.

JOSEPH W. FLAGG, OF WORCESTER, MASSACHUSETTS.

AUTOMATIC CASH-CARRIER.

SPECIFICATION forming part of Letters Patent No. 274,302, dated March 20, 1883.

Application filed May 9, 1882. (No model.)

To all whom it may concern:

Be it known that I, JOSEPH WALTER FLAGG, a citizen of the United States, residing at Worcester, in the county of Worcester and State 5 of Massachusetts, have invented a new and useful Improvement in Automatic Cash-Carriers, of which the following is a specification.

My invention relates to the arrangement of a system of inclined tracks and rolling cash-carriers adapted to the transmission of cash between a cashier's desk and the different locations in a store occupied by salesmen, said system consisting of an inward track to the cashier's desk, with one or more receiving-stations, and an outward track from the cashier's desk, with one or more delivering-stations; and my invention consists in the peculiar arrangement of tracks at the receiving-stations; in the device for retaining the carrier in the 20 elevator and emptying the same onto the track; in the peculiar construction of the outward track, by which the several carriers are properly distributed to their respective stations; in the use of elastic pockets with elastic cushions at their lower extremities, and in the construction of the carriers.

The accompanying drawings illustrate my invention, in which Figure 1 shows an elevation of an outward and inward track with 30 three delivering and receiving stations, and illustrates the operation of transmitting carriers to and from the cashier's desk. Fig. 2 is a plan view of the inward track and its receiving-stations. Fig. 3 is a plan view of the outward track and its delivering-stations. Fig. 4 shows the elevator on an enlarged scale. Fig. 5 is a view of the carrier with the two halves slightly separated. Fig. 6 is a plan view of the lower half, K', of the carrier, the 40 upper half, K, having been removed; and Fig. 7 is an elevation of the pocket for the reception of the carriers, showing the cushioned end.

Similar letters refer to similar parts in the 45 several views.

The several inward and outward tracks are supported overhead by posts resting upon the floor, by brackets reaching from the sides of the store, or by suspension from the ceiling, as 50 may be most convenient. Supports are not shown in the drawings.

The inward track, A A, is formed of two parallel rails, and has an inclination toward the cashier's desk. At the higher end, and at two intermediate positions, are shown stations 55 for the reception of cash-carriers. At each station a short section of track is rigidly fixed to and supported above the track A A, as at C C' C''. These tracks are above and directly over the main track, running in the same direction, and elevated to allow carriers to pass beneath them; but at C' and C'' the elevated tracks make a quarter-turn, c, in order to receive the carriers from the side of the track. At each of the stations vertical guide-rods b b 65 direct an ascending elevator, which may be raised by a cord, l, attached to the top of the elevator at e, and passing over the pulleys m, terminating in the hand-ring n.

The cash-carrier consists of a ball formed in 70 two hemispheres, K and K', Fig. 5, each containing half of the spherical cavity P P, the upper hemisphere shutting over the cylindrical projection on the lower hemisphere, like the cover of a box. This projection has the 75 two short screw-threads L' L', fitting a female thread in the interior of the half K, so that a turn of a partial revolution serves to draw the two hemispheres together. In the edge of the lower hemisphere, K, are the rubber cushions 80 f f', which are compressed as the two hemispheres are screwed together, and prevent them from becoming loosened while in transit. Each of the carriers is covered with leather, rubber, or any similar elastic material, as shown 85 at P' P', Fig. 6, and in section in Fig. 5. The cash is placed in the interior cavity, P P, of the carrier, which is raised by the elevator shown in Fig. 4, which consists of a platform, F, back G, bail H, with a ring or hook, e, at the 90 top, and the tilting shelf J, pivoted in front of the center at I and forming an acute angle with the back G, which incloses and securely holds the carrier S during its ascent. At the front of the shelf J projects the tongue J', 95 which, as the elevator is raised, strikes against a bar, J'', Fig. 3, raising the rear of the tilting shelf J to the position shown by the broken lines at J''', Fig. 4, discharging the carrier onto the receiving-track.

In Fig. 1, D represents a carrier in such a position in the elevator. It will at once roll

along the short elevated receiving-track C, fall a short distance onto the inward track, A A, pass beneath the two receiving-tracks C' and C'' at the two intermediate stations, and be caught by the carrier D'', which already rests against the yielding stop O. The stop O is formed of light steel or other spring wire, rising vertically from each of the two rails and forming a semicircular curve in a horizontal plane to receive the carrier, the vertical sections yielding slightly to the impact of the carrier, thereby preventing the noise caused by the use of a rigid stop. At the second station the elevator, passing up by the side of the track A A, discharges its carrier D' onto the receiving-track C', which is curved for that purpose, the carrier passing on beneath the track C'' to its destination. Thus it will be seen three stations may make use of the same inward track, A A, other stations being added as required, each station from the cashier's desk using carriers of an increased diameter, varying about three-sixteenths of an inch each, the more remote stations using the larger carriers. By the side of or underneath, as shown in Fig. 1, is the outward track, B B, having an inclination from the cashier's desk, and on which the carriers may be returned to the several salesmen at their respective stations. The returning-track B is formed of two parallel rails until the first station, E, is reached, Fig. 3, where the rails curve outwardly, the curve on the inner side of the rails forming the arc of a circle whose diameter is equal to the diameter of the smallest carrier in use on the track, and forming an opening between the rails just wide enough to permit carrier D'' to fall through. The rails, after leaving station E, proceed in lines TT, tangential to the curves at E, the track gradually approaching its normal width until the second station, E', is reached, when the rails are again spread apart by curved sections whose diameter just equals the diameter of the next larger carrier, D', which the opening permits to fall through. The rails then, forming a tangent to these curves, proceed, as before, to the third station, E'', where, as it is the last station on the track B, the rails form a circular opening inclosing the end of the track. If the three carriers D D' D'' sent to the cashier's desk on track A A be returned on track B B, the largest, D, will roll over and across the openings at stations E and E' and fall through that at E'', carrier D' will roll across E and fall through E', and D'' will fall into E. The tangential sections TT of the rails, at the side of exit of each of the openings E E', avoid any shoulders or abrupt turns in the rails and permit the carriers to roll easily out of any opening too small to allow the carrier to fall through.

From the under side of the track B B, at each of the stations E E' E'', two or more stay-rods, *aa*, extend downward, inclosing a tubular pocket, *r*, of wire-cloth, canvas, or some elastic material, so the partial elasticity of the pocket

may to some extent check the fall of the carrier as it strikes against the bottom of the pocket. At the lower end of such tubular pocket I use a metallic shell or case, M N, attached to and supported by the wire-cloth, canvas, or semi-elastic tube, and sliding vertically on the stay-rods *aa*, said metallic shell or case being a continuation of the wire-cloth, canvas, or semi-elastic material forming the tube or pocket, and furnishing a solid support for the door K''. Upon the bottom N, I place the spring *h*, or any equivalent elastic substance, and also a movable bottom or washer, *g*, to receive the impact of the carrier S', the elastic cushion *h* and the semi-elasticity of the tube *r* both serving to check the force of the falling carrier; or either the cushion or the elastic tube may be separately used for the purpose. The door K'' permits access to the interior of the pocket. 85

At each of the cross-ties upon which the rails rest I place small blocks of rubber or elastic material, *t t*, in order to deaden the noise of passing balls, which is also effected in part by the covering of leather, rubber, or similar material, P' P''.

I am aware that a system of inclined tracks has been before in use with carriers consisting of balls with an interior chamber or cavity, the carriers being drawn up to the tracks by elevators. Such I do not claim, broadly; but

What I do claim as my invention, and desire to secure by Letters Patent, is—

1. The combination, with the inward inclined track, A A, of the rigid receiving-track C, said track C being elevated above and directly over the track A A, so the carriers on the track A A may pass beneath it, the rails of the track C being in the same vertical plane as the corresponding rails of the track A A, as shown and described, and for the purpose set forth. 100

2. The combination, with the inward inclined track, A A, of the rigid receiving-track C', said track C' being elevated above and directly over the track A A, so the carriers on the track A A may pass beneath it, the rails of the track C' being, at its lower end, in the same vertical plane as the corresponding rails of the track A A, and at its upper end curved, as at *c c*, so as to receive the carrier from the side, as shown and described, and for the purpose set forth. 110

3. The combination of the inward inclined track, A A, having a tripping-bar, J'', and an elevator having a tilting shelf, J, and a vertical back, G, said shelf and back forming an acute angle, in which the carrier rests, as and for the purposes set forth. 120

4. The elevator consisting of platform F, back G, tilting shelf J, pivoted at I, and forming, with the back G, an acute angle to hold the carrier, and means for elevating the same, in combination with track A A and suitable tripping mechanism, as and for the purposes set forth. 125

5. In an automatic cash-carrying system, the combination, with an inward inclined track, A, of an outward inclined track, B, having one or

more circular openings, E' E'', of varying diameters, and having the portions T T of the rails on one side of said openings tangents to the curved sides of the openings, as and for the purpose shown.

5 6. In an automatic cash-carrying system having rolling cash-carriers of varying diameters, an outward distributing-track, B, having one or more circular openings, E E' E'', of varying widths, and having the portions T T of the rails on one side of said openings tangents to the curved sides of the openings, as and for the purpose shown.

7. The combination, with an outward distributing-track, B B, of the tubular pockets r r r, having sides formed of some elastic material in order to check the force of the falling carrier, as and for the purpose set forth.

8. The combination, with the pockets r r r, attached to the outward distributing-tracks, B B, of elastic cushions placed in the bottom of said pockets to check the force of the falling carriers, as shown, and for the purpose specified.

9. The carrier consisting of the hemispheres K K', with an interior cavity, P, and provided with the screw-threads L' L', or suitable means of attachment, and having elastic cushions f f between the meeting edges of the hemispheres, as set forth.

10. The carrier consisting of two hemispheres, K K', with interior cavity, P, screw-threads L' L', or suitable means of attachment, and having a covering of leather, rubber, or other similar material, as and for the purpose shown.

11. The combination, with a semi-elastic tube, r, of a shell or case, M N, forming a bottom or pocket attached to the semi-elastic tube r, and sliding on the stay-rods a a, as and for the purpose shown.
